UNITED STATES PATENT OFFICE.

LE ROY BURDETT, OF CHICAGO, ILLINOIS, ASSIGNOR TO MESSENGER PUBLISHING COMPANY, INC., OF CHICAGO, ILLINOIS, A CORPORATION OF ILLINOIS.

SHEET-BINDING MACHINE.

Application filed January 10, 1927. Serial No. 160,269.

The present invention relates to sheet binding machines. In the particular instance herein shown it relates more specifically to machines for automatically binding one end 5 of a sheet or of a plurality of sheets of such thin material as paper with a thin metal strip and securely fastening at the ends of such strip suitable means such as a string in the form of a bail for supporting the assembled 10 and bound sheets in hanging position.

Such leaves or sheets of paper may constitute a calendar, for instance what is generally known as an art calendar, or a single-sheet calendar, wherein it is desired to bind 15 the sheet or sheets at one end and with supporting means attached. In the following specification the invention will be described in connection with the binding of sheets generally denominated herein as a calendar.

20 The usual method of forming and binding a calendar comprising a plurality of leaves or sheets of paper has been first to assemble such sheets properly arranged, one set upon another, in stack form, by means of an automatic collecting machine well known in the art. Such a pile or stack of sheets containing many calendars is then given an application 25 of glue at the edges to be bound. After the glue has dried the individual sets of the complete calendars are stripped from the stack. Metal binding strips having a bend along one side thereof having been prepared 30 by cutting and forming operations, one of these is crimped upon the glued edge of each 35 set of sheets, and during one of the numerous operations involved a piece of cord has had its ends secured by the metal strip at the ends respectively of such strip through manual operations.

40 The prime object of the present invention is to provide a machine which will automatically perform all the necessary operations of affixing the binding strip upon edge portions of assembled sheets and, when desired, 45 to include in such automatic operation the assembling and securing therewith of a hanger or supporting means, for example a piece of string forming a bail, for hanging the calendar upon a hook or nail. It is an 50 object to provide such a machine according

to which the output will be rapid. Another object is to provide a machine of the character described which will take the assembled leaves or sheets direct from the collating machine in its normal operation whereby no 55 additional handling or other operation is required. A general object is to save time and money in the production of calendars and like assemblies suitably bound. Specific objects are to provide improved means for performing 60 specific steps in the operations of assembling and binding such sheets. Another object is to provide such a device in compact form, occupying comparatively little space on the floor. A further object is to provide 65 a machine for accomplishing such results which is so arranged as to its respective parts and so constructed as to details as to be strong and durable, and which will consume 70 but a fair and reasonable amount of power.

Various other objects and advantages in construction and arrangement as well as in results will appear hereinafter.

In the accompanying drawings, which form a part hereof, Figures 1 to 6 inclusive, 75 when placed as illustrated in the diagrammatic sheet-layout of Fig. 43, show a complete top plan view of a machine embodying my invention, except that certain parts have been omitted for clearness of illustration, 80 such parts being shown in other views, and in Figs. 5 and 6 certain parts have been broken away to show otherwise hidden parts;

Figs. 7 to 11 inclusive, when placed as shown in the diagrammatic sheet-layout of Fig. 44, are a complete front elevation of the machine;

Figs. 12 and 13, when positioned end to end, show the rear elevation of the machine;

More particularly, Figs. 1 and 2 show in 90 top elevation the driving mechanism and the auxiliary conveyor between the collecting machine and the binding machine for conveying the calendar sets to the binder. Fig. 2 shows also part of one end of the conveyor 95 for the binding machine;

Fig. 3 is a top elevation continuing the binder conveyor, showing the calendar stringing unit, and part of what I shall term the calendar binding unit;

Fig. 4 is a top elevation continuing the binder conveyor and a part of the "binding unit" and showing the "crimping unit" and the "pressing unit;"

5 Figs. 5 and 6 are top elevations of the rear end of the main conveyor. Part of the conveyor is broken away to show the driving and gearing mechanism for the machine;

Fig. 29 is a lateral section of the binding unit taken along the line 29—29 of Fig. 26;

100 Fig. 30 is a fragmentary vertical section of the binding unit taken along line 30—30 of Fig. 28, showing the mandrel and press for bending and pressing the metal strip over the end of the calendar;

105 Fig. 31 is an enlarged fragmentary sectional view of the metal strip bender and press shown in the normal position;

Fig. 32 is an enlarged fragmentary sectional view similar to Fig. 31, shown in the operated position;

110 Fig. 33 is an elevation of the right side of the crimping unit, the conveyor and frame being shown in transverse section;

Fig. 34 is an enlarged partial view of the crimping unit shown in transverse section on line 34—34 of Fig. 10;

115 Fig. 35 is a transverse section along line 35—35 of Fig. 6 showing the right side of the pressing unit in elevation;

Fig. 36 is a transverse section along the line 36—36 of Fig. 11 showing the pressing unit;

120 Fig. 37 is an enlarged partial view of the pressing unit, similar to Fig. 36, the parts being shown in the operated position;

Fig. 38 is a fragmentary top sectional view along line 38—38 of Fig. 37, showing in the normal position one of the duplicate string spreaders;

125 Fig. 39 is a fragmentary front elevation of the duplicate string spreaders shown in the normal position;

Fig. 40 is a fragmentary view of the calendar after the pressing unit has flattened the metal strip;

130 Fig. 41 is a face view of the complete calendar or similar device bound in the manner to be described hereinafter in connection with the description of the present binding machine;

Fig. 42 is a diagrammatic top plan of the binding machine showing the relative positions of the various units;

135 Figs. 43 and 44 are diagrammatic views showing the layout of the sheets of these drawings to obtain complete top and front elevational views of the machine;

140 Figs. 45, 46 and 47 are side elevations showing the contours of the cams that operate the jogging mechanism;

145 Fig. 48 is a top plan of the sheet gripper;

Fig. 49 is a rear elevation of the sheet gripper;

Fig. 50 is a side elevation of the sheet gripper, showing the fingers in the open position;

Fig. 51 is a view similar to Fig. 50 showing the fingers in the closed position;

Fig. 52 is a top plan of the jogging mechanism, the top of the conveyor being removed to show the hidden parts.

Brief description of operation.—The operation of the machine illustrated and embodying my invention is briefly as follows:

Referring to Fig. 42, I preferably employ 15 as an adjunct a suitable collecting or gathering machine, well known in the art, to collect the various sheets of paper into a unit of assembled sheets. So far as the binding operations are concerned a sheet unit may be 20 one sheet or comprise a plurality of sheets. The sheet units being delivered to a conveyor of the collecting machine they pass to an auxiliary conveyor which carries them forward for delivery to the binding machine 25 proper shown as extending at right angles to the auxiliary conveyor.

The collecting machine, the auxiliary conveyor and the binding machine are driven, through suitable clutch and gearing mechanism 30 by a common motor, assuring synchronization in operation.

Before beginning travel on the main conveyor the assembled sheets of each unit are arranged symmetrically with respect to each 35 other by jogging mechanism, operated by cams on the drive shaft of the binding machine. The thus-adjusted sheets are then pressed upon by grippers on the conveyor and are carried forward in a fixed path of travel. 40 The conveyor is advanced intermittently, step by step, with a period of rest between the intermittent movements, and the sheet unit is thus brought successively into position to be operated upon by different mechanisms 45 each performing a part of the entire binding operation.

The various binding operations upon the unit are performed during the rest periods intervening between the successive steps of the conveyor movement. The conveyor and the associated operative units are operated by a common drive, and the functioning of each of the various operative machine units is accomplished during one revolution of the drive shaft. That is to say, during each revolution of the drive shaft the conveyor is advanced one step and a rest period ensues, and each of the machine units performs its operations—these machine unit operations occurring in the latter part of the drive shaft revolution. This assures a perfect timing in the operations of the various units of the binding machine and makes for speed in production.

Assuming that a bunch of sheets has been 65 "jogged" and taken by the grippers, on the

first step of the intermittent movement of the conveyor the sheet unit is advanced into position for work upon it by the stringing unit, which punches or pushes the ends of a loop of string through the sheet unit at each 70 corner and adjacent to the edge portion to be bound. The next step of the conveyor positions the calendar for engagement by the binding unit, and at the same time the next set of grippers has carried another sheet unit 75 into position for engagement by the stringing unit.

The binding unit operates to make a single fold in a binding element and to apply it to an edge portion of the assembled sheets. This 80 binding element or strip is preferably of tin, and through the folding operation it is secured, together with the bail, at the edge of the calendar.

The calendar is then carried forward another step, always remaining held by the grippers which initially took hold of it, and is positioned adjacent to what I will term the crimping unit. This unit operates to crimp the binding element a second time over 90 itself, this time including the extreme edge portion of the sheet unit within the fold.

At the next step the sheet unit is operated upon by the pressing unit, the crimp there being flattened, securely binding the edge of the 95 calendar or other sheet unit.

By the next step of the conveyor the bound calendar is delivered to a table at the end of the conveyor, where it is released from the gripper and deposited into a suitable receptacle or taken away by hand.

Drive and auxiliary conveyor.—Referring to Figs. 1, 2, 7 and 8, an auxiliary conveyor is provided for delivering the sheet units or calendars to the conveyor of the binding machine. The auxiliary conveyor is positioned at the end of the collecting machine, not shown. The frame consisting of a bed plate 1 having upright standards 2 securely bolted thereon is securely fastened to the floor, and one end of the bed plate is bolted to the frame of the collecting machine. A drive shaft 3 for driving the auxiliary conveyor is mounted in suitable bearings in upright standards 2.

Another frame consisting of a base 4 having upright members 5 is securely fastened to the bed plate 1 in alignment with the standards 2 and mounted a short distance away therefrom. A longitudinally extending arm 6 of the upright member 5 is bolted to the 110 frame of the binding machine. The tie rod 7 serves to make the supporting structure rigid.

The upper part of the standards 2 form a bearing for the transverse shaft 8. On one side of the upright standards 2 bearing brackets 11 are securely fastened to support the transverse shaft 13, and on the other side of the standards the brackets 32 are securely fastened. Mounted on the outer ends of the brackets 32 is a transverse bar 33 having ver- 125 130

tically extending members 34 near the outer ends. Secured to the members 34 are guide plates 35 forming the side walls of the auxiliary conveyor. The guide plates extend longitudinally between the guide plates of the collecting machine (shown in dot and dash lines on Fig. 1) and the platform of the conveyor of the binding machine. Brackets 38, secured to the plate 39 fastened to the under side of the binding machine platform, support the other end of the guide plates 35. The tie rod 40 serves to hold the plates rigidly.

Mounted on one end of the drive shaft 3 is a bevel gear 17 for driving the auxiliary conveyor through suitable gearing, including the gear 16 mounted on the outer end of the shaft 3. The gear 16 meshes with the idler gear 15 mounted on the outer standard 2, which in turn drives the gear 14 fixedly mounted on the shaft 8. Keyed on the outer end of the shaft 8 is the gear 9 adapted to mesh with the idler gear 10, secured to the outer bracket 11. The idler gear 10 drives the gear 12 rigidly mounted on the outer end of the transverse shaft 13. Mounted on the shaft 13, inwardly adjacent to the bearing brackets 11, are pulley wheels 24 and 25 respectively carrying the belts 26 and 27 forming a movable support for the sheet units. Also mounted on the shaft 13, inwardly adjacent to the pulleys 24 and 25, are sprocket wheels 28 and 29 driving the endless chains 30 and 31 respectively. The chains 30 and 31 drive the sprocket wheels 41 and 42 securely mounted on the shaft 37. The belts 26 and 27 pass around the pulleys 43 and 44 respectively, these pulleys being also mounted on the shaft 37. The shaft 37 is supported by the vertical bearing brackets 36 integral with the upper part of the frame members 5.

The endless chains 30 and 31 pass over the horizontal supporting plates 45 and 46, to maintain the upper part of the chains horizontal. These supporting plates are securely mounted on the vertical members 34 of the cross bar 33. The chains are maintained taut by the idler sprockets 47 and 48 mounted on brackets supported by the upper part of the frames 5. Vertically extending lugs 49 and 50, forming a part of a cross link of the chains 30 and 31 are spaced equidistantly and in transverse alignment on the chains 30 and 31.

The sprocket wheel 22 centrally disposed between the guide plates 35, is securely mounted on the shaft 8 to drive, through an endless chain 23, a sprocket wheel associated with the conveyor of the collecting machine. A part of the conveyor of the collecting machine is shown in dot-and-dash lines in Fig. 1. Vertically extending pins 51, forming a part of a cross link of the chain 23, are adapted to push the units of assembled sheets forward to and upon the auxiliary conveyor. The lugs 49 or 50 on the chains 30 and 31 of the

auxiliary conveyor push the sheet units further forward. The longitudinally extending rod 52, in alignment with the chain 23, prevents the sheet units from sagging when pushed forward by the conveyor.

The sheet units pass under the roller 53, suitably supported above the rod 52, and, by abutting against the flat spring 54 pivotally mounted and carrying a weighted end, are preliminarily and approximately adjusted or arranged with respect to each other.

A sprocket wheel 18 is securely mounted on the shaft 3 between the standards 2 and near the outer standard and carries an endless chain 19 driving a sprocket wheel 20 mounted on the shaft 21. The shaft 21 is mounted on vertically projecting bearing members 55 integral with longitudinally extending arms of the frame 5. Securely mounted on the shaft 21 is the cam 56. The cam 56 is adapted to operate a roller 57 supported by a downwardly extending arm of the rocker frame 58. The rocker frame 58 is pivotally supported at 59 by longitudinally and vertically projecting arms 60 securely fastened to the frames 5. The rocker frame 58 is of substantially inverted L shape, and at the ends of the longitudinally extending arms carries a shaft 61. Securely mounted on the shaft 61 are pallet wheels 62, approximately in alignment with the belts 26 and 27. Positioned below the pallet wheels 62 are rollers 63 supported by the plate 39. Mounted on the inner end of the shaft 61 is a gear 64 adapted to mesh with a gear 66 which is mounted, together with a sprocket wheel 65, on the inner arm of the rocker frame 58. Securely mounted on the inner end of the shaft 21 is a sprocket wheel 68 carrying a chain 67 which passes over the idler sprocket wheels 69 and 70 supported by lugs on the arms 60, to drive the sprocket wheel 65.

By the action of the cam 56 against the roller 57 the rocker frame 58 is rocked on the pivot 59 to cause the pallet wheels 62 to engage the rollers 63. The sheet units being pushed forward by the lugs on the driving chains 30 and 31 are run onto the conveyor of the binding machine by the rotation of the pallet wheels.

Mounted on the bed plate 1 are vertical bearing supports 71 carrying the main drive shaft 72. The pulley wheels 73 and 74 are securely fastened on the shaft 72 between the bearing supports 71. The pulley wheel 73 is driven by a belt 75 from a motor not shown. The pulley wheel 74 drives, by a belt 76, any suitable air blower, not shown, for several purposes hereinafter described.

A pinion gear 77 is keyed on the drive shaft 72 at its outer end, and is adapted to mesh with the ring gear 78 loosely mounted on the shaft 79. The shaft 79 is mounted in suitable bearings 81. At one end of the shaft the bearing 81 is supported by the frame of the

collecting machine and at the other end the bearing is integral with the vertical bearing support 71. Any suitable clutch 80 may be employed to cause the freely rotating ring gear 78 to transmit power to the shaft 79. Securely mounted on the shaft 79 adjacent to the bearing standard 71 is a bevel gear 82 adapted to mesh with the bevel gear 17 to drive the auxiliary conveyor, as previously described. Securely mounted on the shaft 79 and adjacent to the bearing 81 supported by the frame of the collecting machine is a gear 83 adapted to mesh with an idler gear 84, which in turn drives the gear 85 securely mounted on the end of the shaft 86. The drive shaft 86 is supported at one end by the vertically extending bearing bracket 87 securely fastened to the frame of the collecting machine. The idler gear 84 is mounted upon a vertically projecting arm of the bearing bracket 87.

The collecting machine is driven through a suitable gear train not shown adapted to mesh with the gear 83. The longitudinally extending shaft 86 is supported at its other end by the bearing 88 (Figs. 8 and 9) securely fastened to the frame of the binding machine. Adjacent to the frame of the binding machine is a double bearing standard 89 (Figs. 2, 8 and 9) securely fastened to the floor. The shaft 86 is also supported by one of the bearings and mounted securely thereon. Adjacent to the bearing is the bevel pinion gear 90 adapted to mesh with the bevel gear 91 keyed on one end of the shaft 92. The shaft 92 is supported by the other bearing of the standard 89, and substantially at right angles to the shaft 86. The shaft 92 drives the binding machine. A rod 93 having a handle 94 (Fig. 12) secured to one end is slidably supported by a bracket bolted on the frame of the binding machine. The rod 93 extends longitudinally and parallel to the binding machine and at its other end is secured to one end of the arm 95 securely mounted on the rod 96. The rod 96 (Fig. 9) is supported at one end by the vertical angle iron 97 fastened to the floor adjacent to the binding machine and is secured at its upper end by a bracket to the frame of the binding machine. The other end of the rod 96 is supported on the frame of the collecting machine and carries an arm 98 linked to the downwardly projecting rod 99. The lower end of the rod 99 is connected through any suitable arms and links to the lower end of the collar arm that causes the clutch to be operated through its associated mechanism.

Thus it will be seen that when the operator causes the clutch to be engaged power is transmitted to drive the collecting machine and the binding machine and the auxiliary conveyor.

Main conveyor, jogger, etc.—The main conveyor extends longitudinally, substantially

horizontally, the entire length of the binding machine.

Referring particularly to Fig. 14, 100 represents as a whole the main frame or support by which the other parts of the binding machine are carried, either directly or indirectly. The frame illustrated consists of sections of pipe and appropriate couplings and is suitably secured to the floor. It has vertical supports 101 regularly spaced apart by means of the longitudinally-extending pipes 102 joined to the vertical supports, throughout the length of the binding machine. Adjacent to the floor the transverse pipes 103 are joined to each of the vertical supports 101. Suitably secured to the upper end of each of the vertical supports are the substantially horizontal and parallel bars 104 and 105 extending substantially the entire length of the binding machine. The longitudinal bars 104 and 105 support, by means of the angle brackets 106 which are spaced apart longitudinally and suitably secured thereto, the substantially horizontal parallel bars 107 and 108. The transverse angle braces 109 bolted to the brackets 106 make the supporting structure more rigid. The endless chain conveyor is disposed between the parallel bars 107 and 108. The parallel bars 107 and 108 and the conveyor form a table upon which the sheet units or calendars rest to be moved forward by the intermittent step-by-step movement of the endless chain conveyor.

Referring to Fig. 8 the shaft 111 is supported in bearings 110 mounted on the parallel bars 104 and 105 at the end thereof adjacent to the auxiliary conveyor. The shaft 113 is supported in bearings 112 mounted on the opposite end of the parallel bars. (Figs. 5 and 6.) Mounted on the shaft 111 between the bars 107 and 108 are the sprocket wheels 114 and 115, and mounted on the shaft 113 are the sprocket wheels 116 and 117. The sprocket wheels carry the endless chains 118 and 119. The inner cross links of the chains 110 are formed with an outwardly-projecting flange 120 to which the flat rectangular bar sections 121 forming the movable table are suitably secured. The flat bar sections 121 are made of light metal such as aluminum or of thin wood in order to reduce the weight of the moving conveyor. The flat bars in assembly form a substantially horizontal table which is prevented from sagging by the longitudinal bars 122 and 123, Fig. 14, supported by the angle braces 109, over which the endless chains 118 and 119 slide as the conveyor is advanced.

It has been mentioned that the drive shaft 92 is driven by the drive shaft 86, Fig. 2. One end of the drive shaft 92 is supported in the bearing of the standard 89 and at its other end in bearing 124 of the upright standard 125, Figs. 5 and 6.

The bearing 126 of the upright standard 130

125 is disposed at right angles to the bearing 124 and supports one end of the shaft 127. The other end of the shaft 127 is supported by a bearing 128 mounted on the main frame 100 of the binding machine. The bevel pinion 129 is mounted on the end of the drive shaft 92 and is adapted to drive the bevel gear 130 mounted on the shaft 127. The gear 132 is mounted adjacent to the other end of the shaft 127 and is adapted to drive the gear 133 mounted on the jack shaft 131. The jack shaft 131 is supported by the bearings 134 and 135 integral with the auxiliary frame 136 securely fastened to the floor and at one end 15 to the frame 100 of the binding machine. The other end of the frame 136 has a vertically-extending member 137 (Figs. 6 and 11) which supports at its upper end the bearing 138. The bevel gear 139 is mounted on the outer end of the jack shaft 131 and is adapted 20 to drive the bevel gear 140. The bevel gear 140 is mounted on the vertically-extending shaft 141 supported by bearings 142 and 143 secured to the vertical frame member 137. 25 The bevel gear 144 is mounted on the upper end of the shaft 141 and is adapted to drive the bevel gear 145. The bevel gear 145 is mounted on the longitudinally extending drive shaft 146 supported at one end by the bearing 138. The shaft 146 is securely supported at intervals over its length by the bearing 147 mounted on the supporting bracket 148, Figs. 11 and 35, by the bearing 149 secured to the frame of the binding unit, 30 Fig. 10, and at its other end by the bearing 150 mounted on the supporting bracket 151, Fig. 9. The drive shaft 146 is adapted to drive the various units of the binding machine. 35 The conveyor is advanced in an intermittent step-by-step movement by driving mechanism actuated by the shaft 127 and which drives the shaft 113. The cam 152, Figs. 5 and 12, is mounted on the shaft 127 and, working 40 with the roll 153, imparts a reciprocating movement to the arm 154. The arm 154 is pivoted at its lower end in the bracket 155 secured to the floor. The upper end of the arm 154 is linked to the adjusted rod 156 having its other end linked to the arm 157. The arm 157 is loosely mounted on the shaft 158 mounted in bearings supported by the main frame 100 of the binding machine. Mounted 45 on the shaft 158 is a ratchet 159 having spaced projections 160 the faces of which are adapted to be engaged by the pawl 161 mounted on an outwardly projecting lug 162 of the arm 157.

The roll 153 is pressed against the face of the cam 152 by the compression spring 163 carried by the rod 164. One end of the rod 164 is secured to the arm 154 and the other end is slidably supported by the bracket 165 secured to an upright of the frame 100. The 50 cam 152 forces the arm 154 outward, which

pulls the arm 157 forward, and through the engagement of the pawl 161 with a projection 160 of the ratchet 159, rotates the shaft 158. By the continued action of the cam 152 the arm 154 under pressure of the spring 163 70 is permitted to push the arm 157 back so that the pawl 161 engages the face of the next projection 160.

It will be seen that the shaft 158 is rotated intermittently by this reciprocating action. 75 The gear 166 is mounted on the other end of the shaft 158 and drives the gear 167 mounted on the shaft 113. Thus the shaft 113 is driven intermittently, bringing about the intermittent step-by-step advancement of the conveyor. As the conveyor is advanced forward each step its movement is limited by a ratchet 169 which has the same number of projections 170 as the ratchet 159.

The projections 170 face in a direction opposite to that of the projections 160 of the ratchet 159 and are adapted to be engaged by the fixed pawl 171 secured to the frame 100.

Secured to the under side of the collar of the arm 157 is an arcuate arm 172 which lifts the pawl 171 when the rod 156 pushes the arm 157 back, so that it will not engage the face of the projection 170 when the conveyor is again advanced.

Mounted on the shaft 113 is the disc 168 having the spaced grooves 173 cut in the periphery thereof. As the conveyor is advanced each step, carrying the assembled sheet units, it is centered at each step by the arm 174 forcing the tongue 175 into a groove 100 173. The arm 174 is pivotally supported at its center to the main frame 100 and carries on its lower end the roll 176 which works with the cam 177. The cam 177 is mounted on the jack shaft 131 and has a projecting 105 tongue 178 which forces the arm 174 outward to cause the tongue 175 to enter a groove 173. The roll 176 is held against the cam 177 by the tension spring 179.

The sheets of the respective units, as 110 the units are delivered to the conveyor of the binding machine, are symmetrically arranged by the jogging mechanism and the unit is then securely held to the conveyor by grippers until the unit has been 115 bound. Referring to Figs. 14 and 2, the sheet units are driven onto the conveyor by the friction wheels 62. One edge of the sheet units abuts the angle bracket 180 secured to the under side of the parallel bar 107. One 120 side portion of the sheet units passes under the free ends of the guides 214 associated with the gripper device. Mounted on the drive shaft 146 at its end are the cams 182, 183 and 125 184, Figs. 9 and 14.

The cam 182, as shown in Fig. 46, pushes outwardly the roll 185 (mounted on the bar 186) against the tension of the spring 187. The bar 186 is linked to the arm 188 pivoted by the rod 189 to a supporting bracket secured 130

to the parallel bar 105. The rod 189 carries the upwardly-extending spring fingers 190. When the depressed portion in the periphery of the cam 182 reaches the roll 185 the spring 187 pulls the rod 186 inward and the spring fingers 190 lightly abut the end of the sheet units. Another slight impulse is given the spring fingers when the roll 185 passes over the projection 191 in the depressed portion of the cam 182. This movement by the spring fingers arranges the sheet units symmetrical longitudinally.

The cam 183, as shown in Fig. 47, causes the roll 192 mounted on the bar 193 to impart an oscillating movement to the shaft 194 through the links 195. The shaft 194 is supported in suitable bearings secured to the parallel bars 104 and 105, Fig. 14. Upright members 196 carry the rods 197 projecting inwardly over the conveyor. The rods 197 carry the longitudinally-extending rods 198. Secured to the end of the rods 198 are weights 199 having downwardly projecting fingers 200 which slide in the grooves 201 recessed in the parallel bars 107 and 108. The oscillating movement of the rods 198 cause the fingers 200 to tap the sides of the sheet units against stops carried by the guides 214. This arranges the sheet units laterally.

The grippers for firmly holding the sheet units to the conveyor are mounted at the top of the flat bars 121. The grippers are spaced equidistantly apart longitudinally throughout the conveyor. Each sheet unit, as it is delivered to the conveyor, is arranged and held firmly on the conveyor so as to be advanced step by step to bring its edge portion to be bound into association with the various units which perform the respective binding operations. As each gripper is brought into position to receive a sheet unit from the auxiliary conveyor it is operated so that the gripper fingers are raised to permit the arrangement of the sheet units. By the working of a cam mechanism the gripper fingers are then lowered to hold firmly the arranged sheet units.

Referring to Figs. 48 and 49, the shaft 205 is supported in the bearings 206 and 207 mounted on the shaft bar 121. Mounted on the ends of the shaft 205 are the finger-holders 208. The fingers 209 and 210 are held at their upper ends in circular bands 211 secured to the finger holders 208. The fingers 209 and 210 are made of rubber or any other suitable material. The fingers 209 and 210 are normally pressed against the top of the adjacent flat bar 121 by a spring 212 which has its one end mounted on the bearing 207 and its other end secured to the collar 213 secured to the shaft 205.

Inwardly adjacent to the bearings 206 and 207 the clips 214 are mounted on the flat bars 121. One end of each of the clips 214 is bent upwardly and outwardly to permit the edge 65 of the sheet units to rest against the shoulder

of the clips. The collar 215 is mounted on the shaft 205 and is provided with the lugs 216. A similar collar 217 is mounted on the rod 218 secured to the under side of the bar 121 immediately underneath the collar 215. The collar 217 has projecting lugs 218 linked to the lugs 216 of the collar 215 by the link 219 passing through a slot cut in the edge of the bar 121. A roller 220 is mounted on the lugs 218 to lift the fingers 209 and 210 from the face of the adjacent bar 121.

Securely mounted on the angle brace 109 is the supporting member 221 which carries the slidable plate 222 having an upright roller plate 223 secured thereto. The roller plate 223 is so positioned that when the roller 220 engages the inclined edge 224 of the plate 223 it pushes the link 219 upward to lift the fingers 209 and 210 (Fig. 51). After the sheet units have been arranged by the jogging mechanism as described, the fingers are released by the operation of the cam 184 to hold the sheet units firmly by spring pressure.

The cam 184 moves the roll 203 mounted on the bar 204 slidably supported by the shaft 146. The other end of the bar 204 is secured to the arm 202 (Fig. 52). The arm 202 is mounted on the rod 225 supported by the bracket 226. The arm 227 is secured to the upper end of the rod 225 and is linked to the slidable plate 222. When the plate 222 is pushed back the roller plate 223 is moved away from the roller 220. The fingers 209 and 210 are permitted to take hold of the sheet units immediately before the conveyor is advanced into the next position. Through the driving mechanism the conveyor is advanced into the next position, carrying the sheet unit into association with the stringing unit.

Stringing unit.—The stringing unit is positioned along the edge of the conveyor and functions to punch or push through the sheets the string or flexible bail by which the calendar may be suspended.

Referring to Figs. 10 and 15, the stringing unit is supported by the brackets 230 securely mounted on the main frame of the machine. The frame of the stringing unit consists of a base 231 having side walls 232 and a top wall 233. Secured to the side walls 232 are the vertically extending side arms 234. The upper ends of the side arms 234 extend forward and terminate in the bearings for the cam shaft 235. The transverse angle bracket 236 holds the side arms rigid. Securely mounted on the top wall 233, between the side arms 234, is the frame 236, having the vertically and forwardly extending ribbed frame 237.

The forward end of the ribbed frame 237 is provided with the outwardly extending arms 256. Substantially in the center of the forward end of the frame 237 is the bearing 257 supporting the stub shaft 258.

Bolted to the side walls 232 are the bearing 130

brackets 238 and 239, supporting the drive shaft 240. Mounted on the drive shaft 240 is the bevel gear 241 adapted to be driven by the bevel gear 242 mounted on the main drive shaft 146. The bevel gear 243 is mounted on the shaft 240 and is adapted to drive the bevel gear 244. The bevel gear 244 is mounted on the cam shaft 245 supported by bearings in the side walls 232. The gear 246 is mounted on the cam shaft 245 and is adapted to drive the gear train comprising the gears 247, 248 and 249 securely mounted on the side arm 234. The gear 249 is adapted to drive the gear 250 mounted on the cam shaft 235. The cam shaft 235 and the cam shaft 245 are driven at the same speed.

The forwardly projecting arms 252 are secured to the side walls 232 of the frame. The angle brackets 253 are secured to outer ends 20 of the arms 252 and support the plate 251 extending longitudinally and parallel adjacent to the parallel bar 107. The spacer plate 254, Figs. 16 and 17, is mounted on the top of the plate 251 and supports the thin metal guide plate 255. The guide plate 255 has its corners adjacent to the conveyor bowed upwardly to permit the edge of the sheet unit to pass under the plate easily. The guide plate 255 also serves to hold the edge of the sheet unit while its edge portion is being punched.

The gear 259 is securely mounted on the shaft 258 and is adapted to be rotated by the rack 260. The rack 260 is slidably supported 35 between lugs projecting outwardly from the bearing 257. The plate 261, Fig. 13, secured to the lugs, prevents the rack 260 from moving laterally.

The other end of the rack 260 is secured to 40 the rod 262 connected to one end of the arm 263, Fig. 16. The other end of the arm 263 is mounted on the shaft 264 secured in bearings of the side walls 232. The cam 265 is mounted on the cam shaft 245 and works 45 against the rolls 266 and 267 mounted on the arm 268. The arm 268 is slidably supported on the cam shaft 245 and its outer end is pivoted to the arm 263. By the action of the cam 265 against the roll 266 the arm 263 is 50 pulled forward causing the shaft 258 to be rotated. The roll 267 pushes the arm 263 back and the shaft is rotated back into its first position.

The string gripper 269 is mounted on the 55 shaft 258, under the frame 237. Referring to Figs. 22 and 23 the end of the gripper arm is provided with a slot 270 in which the finger members 271 and 272 are mounted. The rod 273 rests in a groove on the top face of the gripper arm and it is slidably held in the groove by the prong member 274 having one side bent downward over the side of the rod. An upwardly projecting pin 275 is secured in one end of the rod 273 and the other end is 60 connected to the link 276. The link 276 is

mounted on the same shaft as is the finger member 272. The finger members 271 and 272 are discs having downwardly projecting lugs or fingers, the faces of which coincide and are knurled to clutch the string. The gear teeth of the member 272 are adapted to engage the gear teeth of the member 271 to rotate the finger members when the rod 273 is pushed outward, causing the link 276 to rotate its shaft. Mounted on the outer end 70 of the shaft, on which the member 271 is mounted, is the cam 277. The lock member 278 is slidably secured to the side of the gripper arm 269. The end wall of the back member 80 engages the cam 277 to hold the fingers in the open or closed position after they have been operated. The locking member 278 is maintained in engagement with the cam 277 by the spring 279. The spring 279 is inserted in an opening in the end of the locking 85 member and presses against a mounting screw of the locking member, the other end of the spring pressing against a set screw in the opening.

The bar 296 is secured to the gripper 269 to limit the arcuate movement of the gripper arm. When the gripper arm is rotated the ends of the bar 296 abut the downwardly projecting arm of the stop members 297 mounted on the side arm 256 of the frame 237.

Referring to Figs. 17 and 18 the string 280 is threaded in the tube 281 of the string holder 281^a mounted on the plate 251. The string holder is provided with a triangular eye 282 through which the string passes. The side walls of the string holder comprise the spring members 283 shaped to the eye 282 and hold the end of the string. The string holder is pivotally mounted on the plate 251 and on its under side carries the arm 284 connected by the wire 285 to the end of the arm 286. The arm 286 is mounted on the shaft 287 supported by a tube carried by a bracket secured to the plate 251. The arm 288 is mounted on the other end of the shaft 287 and the end of the arm rests in a groove in the parallel bar 107.

When the sheet units are advanced into association with the stringing unit the sheet units pass under the arm 288 causing the arm 115 284 to position the string holder 281^a so that the eye 282 will be centered with the fingers of the string gripper 269. The cam 265 pushes the roll 267 outward, causing the rack 260 to rotate the shaft 258. The string gripper is positioned adjacent to the string holder with its fingers in the open position.

The cam 289 is mounted on the shaft 240 and has outwardly projecting lugs on its face. The roll 290 mounted on the lever arm 291 is 125 pushed outwardly when passing over the lugs. The lever arm 291 is pivotally secured to the side wall 232 and has a rod 292 secured to its upper end. The rod 292 is linked to the plate 293 pivotally supported on the un- 130

der side of the frame 237. The plate 293 is provided with the prongs 294 and 295, adapted to engage the pin 275 of the gripper. When the gripper is in alignment with the string holder the prong 294 engages the pin 275 and pulls the rod 273 to operate the fingers 271 and 272 of the gripper into the closed position. The fingers slide over the spring sides of the string holder and clutch the end of 10 the string projecting out of the eye of the string holder.

The further rotation of the cam 265 causes the roll 266 to operate the gripper 269 into the position shown in Fig. 18. The string 280 is pulled through the keys of the string holder, passing over the top of the sheet units. The string is held by the gripper fingers adjacent to the edge of the sheet units at one side and the string holder holds the string taut adjacent to the edge at the other side.

The cam 298, Figs. 15 and 17, is mounted on the jack shaft which supports the gear 247. The cam 298 works with the roll 299 mounted on the arm 300 slidably supported by the jack shaft. The other end of the arm 300 is linked to the pivoted arm 301 mounted on a block member of the plate 302 secured to the plate 236. The channel plate 303 is secured to the plate 251. The plate 304 is adapted to slide 30 in the channel of the plate 303 and is maintained in the channel by the washer 305 secured to the downwardly projecting member 306 passing through a slot in the bottom of the channel. The arms 307 and 308 are 35 mounted on the plate 304. The other end of the arms 307 and 308 are secured to the lever arms 309 and 310 mounted on the plate 254. The spools 311 are mounted on the outer ends of the lever arms 307 and 310.

When the cam 298 pushes the arm 300 outward by working against the roll 299 the lever arm 301 causes the sliding plate 304 to slide inward in the channel of the plate 303. The arms 307 and 308 affixed to the plate 304 cause the string spreader arms 309 and 310 to spread outwardly. The spools 311 engage the string 280 and force a suitable length through the string holder from a ball of string 312 which may be located on the floor, Fig. 3. The string is positioned over the sheet units ready to be punched through the edge of the paper and the ends of the string cut off at the edge of the sheet units.

The cam 313 is mounted on the cam shaft 235, Figs. 15 and 16. The roll 314 is adapted to roll in the groove 315 in the side of the cam 313 imparting a reciprocating movement to the rocker arm 316. The cam 314 is mounted on the arm 317 secured to the rocker arm 316. The rocker arm 316 is mounted on the shaft 318 supported by the rib of the ribbed frame 236. The arm 319 is mounted on the end of the shaft 318 and its lower end is connected to the arm 321 of the lever 322 by the link 320. The lever 322 is loosely mounted

on the shaft 245 and has an arm 323 connected to the bracket 324 by the link 325. The bracket 324 is secured on the under side of the plate 326 adapted to slide in grooves 328 in the side walls of the angle bracket 327. The bracket 327 is secured to the frame of the stringing unit. The U-shape brackets 329 are mounted on the plate 326 and support the plate wedges 330 secured to the under side of each bracket 329. A plate 331 is secured on the plate 326 and has integral wedge plates 332 projecting vertically.

The angle brackets 333, Figs. 13 and 16, are secured on the under side of the plate 251. The ends of the plate 336 are slidably secured in slots in the brackets 333. The side walls of the U-shape slot in the center of the plate 336 abut the supporting arms 252 preventing longitudinal movement of the plate 336. The rollers 335 are mounted on the narrowed section 334 of the plate 336 and are forced upward by the wedges 332. The narrowed section 334 engages the wedges 330 and the plate 336 is forced downward. The plate 336 carries the duplicate arms 337 the upper end being secured to the duplicate cutting discs 338 and 339. The cutting discs are mounted on the plate 251 immediately underneath the end of the string holder and the fingers of the string gripper. The cutting discs are provided with cutting edges which are brought together when the plate 336 is raised by the wedges 332 engaging the rollers 335.

The rocker arm 316 is provided with forwardly projecting arms provided with slotted ends. The yoke 340 is slidably supported by the guide rods 341 and 342 secured on the arms 256 of the frame 237.

The duplicate punching mechanism is secured to the outer ends of the yoke 340. Referring to Figs. 19 and 20, the punching mechanism comprises the tube 343 in which the punch 344 is threaded. The end of the punch is provided with a V-shaped slot that engages the string. The sleeve 345 is mounted on the tube 343 and is provided with the projecting lugs 346 adapted to fit in the slots in the end of the arm of the rocker frame 316. The angle bracket 347 is secured to the sleeve 345 and supports the guide tube 348 which passes through the arm 256. The punch tube 343 passes through the guide tube 348. The spring 349 maintains the guide tube 348 and the sleeve 345 normally apart.

The cam 313 works against the roll 314 to force the rocker arm 316 downward. The arms of the rocker frame 316, through the pins 346 of the sleeves 345, pull the yoke 340 downward, the yoke being guided by the rods 341 and 342. The guide tubes 348 slide through the arms 256 of the frame 237 and pass through the hole 350 in the string gripper 269, Fig. 21. The downward movement of the guide tube 348 is arrested when the top of the sheet units are reached and the ends

of the tubes hold the edges of the paper firmly against the table plate 251. The slotted mounting of the supporting bracket 347 permits the further downward movement of the punch while the guide tubes rest upon the paper. The V shape slot in the end of the punch 344 engages the string and punches it through the edge of the paper. The slots 351 aligned in the plate 251 permit the punch 344 to pass entirely through the paper.

The rocker arm 316 rotates the shaft 318 causing the arm 319 to pull the lever arm 321 of the lever 322. The lever arm 323 slides the plate 326 outward causing the wedges 332 to push the rollers 335 upward. The plate 336 slides upward in the slots in the angle brackets 333 causing the arms 337 to close the cutters 338 and 339. As shown in the dot-and-dash lines of Fig. 16, the edges of the sheet units are adjacent to the cutters. By the operation of the cutters the string is cut off with the ends 352 even with the edge of the sheet units, Fig. 25.

25 The cam 313 pulls the rocker arm 316 upward and the yoke 340 slides upward on the guide rods 341 and 342, carrying the punch mechanism back into its normal position. The arm 319 causes the lever 322 to pull the plate 326 back into its normal position. The
30 wedges 330 force the plate 336 downward to open the cutting discs 338 and 339. The roll 290 engages a lug on the cam 289 operating the lever arm 291 to pull the rod 292 causing the finger 295 of the plate 293, Fig. 18, to
35 push against the pin 215 to open the fingers 271 and 272 of the string gripper 269. The fragment of string held by the fingers, after the cutters have cut the string the desired length, is sucked into the waste pipe 351,
40 Fig. 3. The suction is created by compressed air blowing into the nozzle of the waste pipe 351 through the feed pipe 352 connected to any suitable compressor (not shown).

The spring 353 pulls the lever arm 301 to slide the plate 304 back in the channel of the plate 303 causing the arms 307 and 308 to pull the arms 309 and 310 of the string spreader back into the normal position as shown in Fig. 17. The cam 265 pushes the roll 267 causing the arm 263 to pull the rack 260 back into its normal position. The gear 259 is rotated by the rack and the string gripper 269 is restored to its normal position as shown in Fig. 17.

55 All of the above described operations of the stringing unit were performed during one complete revolution of the drive shaft 146, beginning with the advancement of the sheet unit into alignment with the stringing unit.

60 The conveyor driving mechanism now operates to advance the conveyor into the next position, aligning the punched sheet units with the next unit, the binding unit. At the same time another sheet unit is advanced into association with the stringing unit where the

65

same operations are performed upon it as upon the preceding one now advanced one step.

Binding unit.—Referring to Figs. 10 and 26, the vertically-extending brackets 360 are secured to the pipe frame 102 and are provided with vertical arms secured to the parallel bar 104. The binding unit is securely mounted on the base plates 361 mounted between the horizontal arms of the brackets 360. The frame of the binding unit consists of the substantially rectangular side walls 362 and 363 having a flanged edge along the front portion of the top. Integral with the side walls 362 and 363 are the vertically-extending arms 365 and 366 supporting at their upper ends the cam shaft 367. The tie rods 368 serve to make the frame rigid. The plate 364 is mounted on the upper end of the side walls, adjacent to the parallel bar 107 of the conveyor. The cam shaft 369 and the shaft 370 are supported in bearings formed by the side walls. Collars are mounted on the outer ends of the shafts 369 and 370 to prevent end play.

The gear 371 is mounted on the cam shaft 369 inwardly adjacent to the side wall 363 and is driven by the gear 373 mounted on the main drive shaft 146 through the idler gear 372 mounted on a stub shaft secured to the side wall 363. The gear 374 is mounted on the shaft 146 outwardly adjacent to the side wall 363 and drives the double pinion gear comprising the gears 375 and 376. The gear 376 drives the gear 377 which drives the pinion gear 378. The gears 377 and 378 are mounted on stub shafts secured to the side arm 366. The gear 378 drives the gear 379 mounted on the cam shaft 367. The cam shafts 367 and 369 are driven at the same speed. 95 100 105

The binder strips, to be applied as the binding, are placed on a table and individual ones are picked up and delivered to the breaker mechanism. These strips in my practice are of tin. The breaker mechanism puts a fold in the strip and bends it over and around the end portion of the sheet unit. Referring to Figs. 10 and 28, the table 380 upon which the binder strips are placed is disposed between the vertical arms 365 and 366. The table 380 comprises the bottom plate 381 having the side plates 382 and 383 securely mounted thereon. The forward end of the plate 381 is secured to the plate 384 which extends transversely between the side walls 362 and 363 and is supported by the brackets 385 and 386 mounted on the flanges of the side walls. The other end of the plate 381 rests upon the plate 387 which is supported by the brackets 388 and 389 secured to the side walls 362 and 363, Fig. 29. A carriage frame is slidably supported on the plate 381 by the angle brackets 394 and comprises the rack arms 390 and 391 having the bars 392

and 393 secured to the ends. The carriage frame is pushed forward by the gears 395 which engage the rack arms 390 and 391. The gears 395 are mounted on the shaft 396 which 5 is supported by downwardly extending bearing arms integral with the plate 381. The pulley wheel 397 is mounted on the shaft 396. The cord 398 is tied to the shaft 396 and is wound around the pulley 397 and supports the weight 399. The weight tends to 10 rotate the shaft 396 and the gears 395 push the carriage frame against the sides of the binding units 400 which are positioned on the table 380. Downwardly projecting springs 15 402 suitably bent are mounted at intervals on the bar 401 which is secured to the brackets 385 and 386. The binder strips hereinabove mentioned are designated 400 and they abut the tips of the springs 402, and the forward 20 ends of the side plates 382 and 383 are bent inwardly to hold the strips 400. The strips 400 are taken from the table 380 one by one as needed while the remaining metal strips are pushed forward by the carriage frame 25 until the foremost strip 400 is held by the springs 402.

Angle brackets 403 are mounted on the brackets 385 and 386 and are provided with slots in which the pins 404 projecting outwardly on the links 405 are adapted to slide. The links 405 are positioned between the vertically-extending sides of the brackets 385 and 403 on the one side of the binding unit 30 and the brackets 386 and the duplicate bracket 403 on the other side. The nozzle 406 is positioned between the brackets 385 and 386 and is supported by end caps provided with pins 408 projecting through the slot 407 in the side of the brackets 385 and 386. The 35 links 405 are mounted on the pins 408.

The nozzle 406 is provided with a plurality of inlets having the rubber caps 416 secured thereto. The caps 416 are forced against the side of the foremost metal strip. The outlet 45 of the nozzle 406 is connected by the flexible tube 417 to the pipe 418. The sprocket wheel 419 is mounted on the cam shaft 369 and drives the sprocket wheel 420 through the chain 421. The sprocket wheel 420 is mounted 50 on the shaft 422 supported by the bracket 423 which is secured to the valve 424. The valve 424 is mounted on the plate 425 which is secured to the side wall 362. The cam 426 mounted on the shaft 422 operates the valve 55 424 through the roll 427. The roll 427 is mounted on the valve lifter rod 428 and is pressed against the cam 426 by the spring 429. The pipe 418 is connected to the valve 424, the latter being connected by the pipe 430 60 to a suitable suction pump (not shown).

The cam 409 is mounted on the cam shaft 367 adjacent to the side arm 365 and works against the roll 410 secured on the arm 411 mounted on the shaft 412.

65 The shaft 412 is supported by the bearing

brackets 413 secured to the side arms 365 and 366. The downwardly-extending arms 414 are mounted on the shaft 412 inwardly adjacent to the side arms 365 and 366. One end of each of the two links 415 is secured to the 70 lower ends respectively of the arms 414, and the other ends of the links 415 are secured respectively to the two pins 408.

The cam 426 pushes the roll 427 upward and the valve lifter rod 428 opens the valve 424. The rubber caps 416 on the nozzle 406 firmly hold the foremost metal strip 400 by the suction of the suction pump. The cam 409 works against the roll 410, and the arms 414 push the links 415 forward. The links 80 415 cause the nozzle 406 to be pushed forward and by the action of the pins 408 in the slots 407 the nozzle is forced downward. The pins 404 of the links 405 sliding in the slots in the side walls of the brackets 403 85 rotate the nozzle 406 carrying a metal strip 400 so that the metal strip 400 is positioned horizontally to be clamped by the clamping members 431 and 432.

The upper clamping plate 431 is slidably 90 mounted in the grooved bars 433 and is supported by the hangers 443 carried on the rod 442.

The grooved bars 433 are supported by the angle brackets 434 on the flanges of the side 95 walls 362 and 363. The rods 435 are secured to each end of the clamping plate 431 and extend upward through the end of the brackets 436 secured to the grooved bars 433. The springs 437 (Fig. 13) are mounted on 100 the rods 435 and push the plate 431 downward. The duplicate cams 438 are mounted on the cam shaft 367 inwardly adjacent to the side arms 365 and 366 and work with the rolls 439 secured to one end of the bell crank 105 lever arms 440. The bell crank lever arms are supported by the stub shafts 441 secured to the side arms 365 and 366. The other ends of the bell crank lever arms 440 are secured to the rod 442 and support the clamping 110 plate 431.

The clamping member 432 is slidably 115 mounted in the grooves 444 in the side walls 362 and 363, Figs. 28 and 29. The bar 445 is mounted on the top of the clamping member 432. The links 446 are secured to the clamping member 432, project downward and are connected to adjustable eye bolts carried by the arms 447 securely mounted on the shaft 370. The cam 448 is mounted on the 120 cam shaft 369. The clamping member 432 is adapted to be raised by the cam 448 working with the roll 449 carried by the arm 450 mounted on the shaft 370, rocking the arms 447 and 450. The arms 447 are connected 125 by the bar 451 mounted on the under side thereof, to hold them rigid.

The cam 452 is mounted on the cam shaft 369 and works with the roll 453 carried by the arm 454 which is loosely mounted on the 130

shaft 370. The roll 453 is pressed against the cam 452 by the spring 455 having one end fixed to the arm 454 and its other end fixed to the link 456 mounted on the upper 5 tie rod 368. The rod 457 is mounted on the upper end of the arm 454 and is secured to the sliding carrier yoke 458. The yoke 458 is slidably mounted on the parallel rods 459. The parallel rods 459 are supported at one 10 end of the bar frame 460 which extends transversely between the side walls 362 and 363 and is supported on the top thereof. The other ends of the parallel rods 459 are secured in downwardly projecting lugs of the plate 15 387. The parallel bars 461 are secured to the ends of the yoke 458 and are adapted to slide in grooves in the frame bar 460. The forward ends of the parallel bars 461 carry the plate 462. The ends of the plate 462 are supported on the top of the side walls 362 and 20 363 and slide in grooves that are cut away in the brackets 385 and 386. Grooves are also cut in the brackets 463 and 464, Figs. 28 and 30, to permit forward movement of the plate 25 462. The spring clips 465 are mounted on the plate 462.

When the foremost binding unit or metal strip 400 has been carried forward and downward, by the movement of the nozzle 406 in 30 the path of travel of the carrier yoke 458, the roll 439 is opposite the depressed portion of the cam 438 and the springs 437 push the clamping plate 431 downward. The cam 448 pushes the roll 449 downward causing the 35 arms 450 and 447 to rock on the shaft 370. The arms 447 push the clamping plate 432 upward by the links 446. The metal strip 400 is caught between the faces of the clamping plates 431 and 432 and is firmly held 40 with its edge against the stop bar 445. Before the metal strip is positioned in the path of travel of the carrier yoke 458, the cam 452 permits the spring 455 to pull the arm 454 carrying the roll 453 rearward. The movement of the arm 454 pushes the rod 457 and 45 the carrier yoke 458 slides back on the rods 459. The plate 462 carrying the spring clip 465 is now positioned back of the clamping members 431 and 432. By the further action 50 of the cam 452 working with the roll 453, the arm 454 and the rod 457 causes the carrier yoke 458 to slide forward on the rods 459. The spring clips 465 engage the metal strip 400 and it is firmly held by being forced between the spring clips. The clamping members 431 and 432 are caused to open by the further action of the respective cams 438 and 452. The metal strip 400 is then carried forward and positioned on the plate 364, Fig. 55 31, by the action of the cam 452 against the roll 453. The metal strip abuts against the stop bar 466 and is firmly held on the plate 364 by the vertical clamp 467.

When the sheet units are advanced into 60 65 position to be operated upon by the binding

unit, the edge to be bound passes over the stop bar 466 and is maintained above the plate 364. The metal strip 400 is thus permitted to pass under the sheet units and abut the stop bar 466. The stop bar 466 is imbedded in the plate 364 and is provided with downwardly projecting rods 467' passing through the supporting blocks 468. The springs 469 are mounted on the rods 467' and push the bar 466 upward so that normally 75 the tip of the bar 466 projects above the surface of the plate 364.

The vertical clamp 467 is mounted above the plate 364 and is supported by the brackets 464 mounted on the side walls 362 and 363, 80 Figs. 3 and 13. The ends of the clamping plate 470 are slidably supported in grooves in the side walls of the brackets 464 and are provided with vertically extending rods 471 which pass through the cover plates 472, Figs. 85 30 and 31. The cover plates 472 are secured on the top of the brackets 464. The springs 473 are mounted on the rods 471 and force the clamping plate 470 upward away from the plate 364. Bearing blocks 473' are 90 mounted on the upper face of the clamping plate 470 and support the shaft 474. The pinion gears 475 are mounted on the shaft 474. The wedge plate 476 is slidably mounted on the upper face of the plate 470 and its 95 ends are mortised in the ends of the plate 470. The wedge plate 476 is provided with the rack flanges 477 which engage the pinions 475. Inwardly projecting pins 478 are secured in the ends of the clamping plate 470 100 and engage the slot in the forward end of the lever arms 479. The lever arms 479 are mounted on the brackets 464 and their upper ends are secured to the ends of the arms 480. The arms 480 are slidably supported on the 105 cam shaft 367 and carry the rolls 481. The duplicate cams 482 are mounted on the cam shaft 367 and work with the rolls 481. The cam 483 is mounted on the cam shaft 367 and works with the roll 484 mounted on the arm 110 485. The arm 485 is slidably supported on the cam shaft 367 and its forward end is secured to the arm 486 which is mounted on the shaft 474. The bracket 488 is mounted on the front of the clamping plate 470 115 and supports the rod 487 having the spring 489 mounted thereon. The rod 487 is secured to the arm 486 and the spring 489 forces the arm 485 to press the roll 484 against the cam 483.

After the metal strip 400 has been brought forward by the carrier 462 and positioned on the plate 364, Fig. 31, the cams 482 cause the rolls 481 to push the arms 480 forward. The movement of the lever arms 479 push the clamping plate 470 downward and securely clamp the sheet units and the binding strip 400 on the plate 364. The stop bar 466 is depressed into the plate 364 by the pressure of the clamping plate 470.

The cam 483 causes the roll 484 to push the arm 485 forward and the movement of the arm 486 rotates the shaft 474. The pinion gears 475 work with the racks 476 and push the wedge plate 476 downward and rearward on the inclined face of the supporting plate 470. The longitudinally extending tip 490 of the wedge plate 476 is brought flush with the bottom of the clamping plate 470 and securely holds the edge of the sheet unit and the string 282 as shown in Fig. 32. The binding strip 400 is firmly held in readiness to be bent over the edge of the sheet unit and the string to bind the sheets together.

Referring to Figs. 28 and 30 the metal strip 400 is bent over the end of the sheet unit by the break mechanism which is mounted immediately under the plate 364. The break frame 491 is provided with the downwardly-extending arms 492 and is pivotally supported on the blocks 468 mounted on the plate 364.

The shaft 494 is secured in the ends of the arms 492. The arm 495 is slidably supported on the cam shaft 369 and is secured to the shaft 494. The cam 497 is mounted on the cam shaft 369 and works with the roll 498 mounted on the arm 495. The rod 496 is mounted on the shaft 494 and carries a spring 499. The end of the rod 496 is slidably supported in the lug 500 projecting inwardly from the side wall 362. The break frame 491 supports the break 501 pivotally mounted on the rod 502. The break 501 is provided with downwardly extending arms 503 carrying the rod 504. The arms 493 are slidably supported on the cam shaft 369 and are secured to the rod 504. The duplicate cams 506 are mounted on the cam shaft 369 and work with the rolls 507 secured to the arms 493. The break 501 is provided with a longitudinally extending tip 505 which serves to bend the metal strip 400.

The plate 364 is provided with an arcuate channel edge 508 in which the tip 505 of the break 501 is adapted to slide. Slots are provided in the channel edge to permit the passage of the arms 503. When the metal strip 400 and the sheet unit are held by the clamp 467, the edge of the arcuate channel 508 and the tip 490 of the wedge plate 476 coincide and the edge of the metal strip 400 projects back in the path of travel of the break 501. The cam 452 permits the spring 455 to pull the arm 454 rearward and the yoke 458 pulls the metal strip carrier plate 462 into its position back of the clamping plates 431 and 432.

The cam 497 working with the roll 498 causes the arm 495 to pull the break frame 491 and the tip 505 of the break 501 slides upward in the channel 508 past the tip 490 of the wedge plate 476. The tip 505 forms a break in the edge of the metal strip 400 along the tip 490. The tip 505 of the break 501 is positioned

above the break in the metal strip 400. The cam 483 working with the roll 484 permits the spring 489 to return the wedge plate 476 into its normal position. The cams 506 push the rolls 507 rearward and the arms 495 rock the break 501 on the rod 502. The under side of the tip 505 presses the break of the metal strip 400 and flattens it over the edge of the sheet units. The sheet unit and the string are securely held by the bend in the binder strip. The rolls 481 reach the depressed portion of the cams 482 and the springs 473 are permitted to open the clamp 467 and the driving mechanism operates to advance the conveyor into position with the next unit, namely the bending unit, and a new sheet unit is brought into position with the binding unit. The new set of sheets as a unit are then bound in the manner described.

Crimping unit.—The crimping unit is positioned one step of the conveyor beyond the binding unit just described. The crimping unit turns the edge of the sheet unit upon itself as shown in Fig. 34.

Referring to Figs. 10 and 33 the crimping unit is supported by the brackets 510 mounted on the frame 100 of the binding machine. The substantially rectangular side walls 511 are mounted on the base plate 512 supported by the brackets 510. The vertical frame arms 513 are mounted on the base plate 512 and are secured to the side walls 511 by the angle brackets 514. The slots 515 are provided in the upper ends of the frame arms 513. The plate 516 is secured on the top of the arms 513 and supports the rearwardly extending brackets 517. The brackets 517 support the rod 518 on which the lever arm 519 is mounted.

The cam shaft 520 is supported in bearings in the side walls 511. The gear 521 is mounted on the main drive shaft 146 and drives the gear 522 which is mounted on a stub shaft supported by the side wall 511. The gear 522 drives the gear 523 mounted on the cam shaft 520, Fig. 34.

The bar plate 524 is slidably mounted in the slots 515 of the arms 513 and is supported by the rods 525, projecting upward through the plate 516. The springs 526 and 527 are mounted on each of the rods 525 and press the plate 524 upward. The upward pressure of the springs 526 and 527 may be adjusted by the nuts 528. The plate 529 is secured to the front of the plate 524 and supports the wedge plate 530. The wedge plate 530 is adapted to be adjusted vertically by the adjusting screws 531. The forwardly projecting rod 532 is mounted on the plate 529 and supports the hanger 533. The bar 534 is slidably mounted in the slot 536 of the hanger 533 and is supported by the vertically extending arms 535. The upper ends of the arms 535 are secured to the outer ends of the arms 537 mounted on the rod 518. The plate 538 is slidably mounted on the bar 534 and is normally pressed

85

90

95

100

105

110

115

120

125

130

downward by the springs 539 secured to the bar 534. The cam 540 is mounted on the cam shaft 520 and works with the roll 541. The roll 541 is mounted on the forked arm 542 which is slidably mounted on the cam shaft 520. The arm 542 extends vertically and is secured at its upper end to the arm 519. One end of the spring 543 is secured to the arm 542 and the other end is secured to the lug 544 mounted on the side wall 511. The spring 10 presses the roll 541 against the cam 540.

The anvil plate 545 rests on the inwardly projecting lugs 546 of the vertical arms 513 and is secured thereto. The anvil plate 545 15 is provided with a groove 570 in which the sliding plate 568 is mounted. The plate 568 is normally pushed upward by the springs 569, which are mounted on guide rods at each end of the plate 568, to close the 20 opening of the groove 570. The groove 570 is directly under the tip 571 of the wedge plate 530. The block 547 is mounted on the front of the plate 545 and supports the transverse plates 548 and 549. The plate 550 is 25 mounted between the plates 548 and 549 and serves to raise the surface of the sheet units when they are positioned in association with the crimping unit. The yoke 551 is slidably mounted on the rods 552 secured to the anvil 30 plate 545. The forwardly extended arms 553 are secured to the yoke 551 and carry the pusher plate 554 at their front ends. The springs 555 are mounted on each of the rods 552 and push the yoke 551 rearward. The vertically extending arm 556 is mounted on the 35 shaft 557 supported by the side walls 511. The upper end of the arm 556 is linked to the yoke 551. The cam 559 is mounted on the cam shaft 520 and works with the roll 558 mounted 40 on the arm 556.

The cams 560 are mounted on each end of the cam shaft 520 and work with the rolls 561 secured to one end of each of the arms 562. The arms 562 are mounted on the shaft 563 45 supported by the vertical arms 513. The brackets 564 are secured to the plate 524 and are provided with downwardly extending arms 565 which are secured to the arms 562 by the rod 566. The spacer rod 567 is 50 mounted between the bracket arms 565.

When a sheet unit is positioned opposite the crimping unit by the operation of the conveyor it slides over the plate 550 which partially raises the bound edge. By the operation 55 of the cam 540 with the roll 541 the arm 542 is pushed upward and the arm 519 causes the arms 537 to push the plate 538 downward in the slot of the hanger 533 until it presses the sheet unit firmly to the surface of the parallel bar 107. The cam 559 works with the roll 558 and the arm 556 pushes the yoke 551 forward on the rods 552. The pusher plate 554 abuts the bound edge of the calendar 60 and pushes the end of the calendar forward so that the metal strip will be positioned over

the groove 570 and under the tip 571 of the wedge plate 530. The cams 560 work with the rolls 561 to push the arms 562 downward and the brackets 564 cause the plate 524 to slide downward in the slots 515. The wedge 70 plate 530 is carried downward and the tip 571 pushes the metal strip 400 into the groove 570 and a crimp is formed in the bound edge as shown in Fig. 34. The sheet units are 75 held firmly by the plate 538.

By the further action of the cam 540 the spring 543 pulls the arm 542 downward to lift the plate 538 from the surface of the calendar. The cam 559 permits the springs 555 to slide 80 the yoke 551 back on the rods 552 and the pusher plate 554 is retracted. The action of the cam 560 permits the springs 526 and 527 to return the wedge into its proper position. The springs 569 push the plate 568 upward 85 and force the crimped edge of the binder strip out of the groove 570.

The pressing unit.—The calendar is now advanced into association with the pressing unit by the action of the conveyor and the crimped edge of the sheet unit is then flattened to complete the binding of the calendar. The frame of the pressing unit is similar to that of the crimping unit, and is supported 90 on the brackets 572 mounted on the frame 100 of the binding machine, Figs. 11 and 36. The side walls 573 are mounted on the base plate 574 supported by the brackets 572. The vertical frame arms 575 are mounted on the base plate 574 and are secured to the side walls 573 by the angle brackets 576. The slots 577 are provided in the upper ends of the frame arms 575. The plate 578 is mounted 95 on the top of the arms 575 and is provided with the forwardly extending bracket arms 579. The bracket arms 579 support the cam 100 shaft 580.

The duplicate cams 597 are mounted on the cam shaft 580 and work with the knobs 598 mounted respectively on one end of each of the vertical shafts 599. The shafts 599 are 110 slidably supported in the bearings 600 projecting forward from the plate 579. The pinion gears 601 are slidably keyed to the shafts 599 and work with the rack rods 602. The racks 602 are slidably mounted in grooves in the under side of the plate 578 and are supported by the plates 603. The pinion gears 604 are mounted on the other end of each of the vertical shafts 599. The springs 605 are mounted 115 on the shafts 599 and press the knobs 598 against the cams 597.

The cam shaft 581 is supported in bearings in the side walls 573. The gear 582 is mounted on the cam shaft 581 and is driven by the gear 583 mounted on a stub shaft supported by the side wall 573. The gear 583 is driven by the gear 584 mounted on the main drive shaft 146.

Referring to Fig. 35 the sprocket wheel 585 is mounted on the end of the cam shaft 581 130

and drives the chain 586. The chain 586 drives the sprocket wheel 587 mounted on the cam shaft 580. The chain 586 is maintained taut by passing over the idler wheel 588 mounted on the bracket 589 secured to the bracket 576.

The bar plate 590 is slidably mounted in the slots 577 of the arms 575 and is supported at each end by the rods 591 projecting upward through the plate 578. The springs 592 are mounted on the rods 591 and press the plate 590 upward. The upward pressure exerted on the plate 590 may be adjusted by the nuts 593. The plate 594 is secured to the front of the plate 590 and supports the pressing plate 595. The string spreader mechanism 596, as shown in Figs. 4 and 12, is mounted on the plate 595 and comprises the duplicate spreader arms which are slidably mounted at each end of the plate 595. The spreader arms are similar as to construction except when operated one moves to the right end and the other moves to the left end of the plate 595. Referring to Figs. 38 and 39, showing the left hand spreader arm and a portion of the right hand spreader arm, the racks 606 are slidably mounted in the grooves 607 in the front of the plate 595 adjacent to the bottom. The racks 606 are provided with the forwardly projecting lugs 608 at each end. A plate 610 is mounted on the end of each of the shafts 599 and is provided with the slot 611 which permits lateral sliding movement on the shaft 599. The slotted lugs 609 project upwardly from the rear of the plates 610 and the lugs 608 of the racks 606 fit into the slots of the lugs 609. The supporting brackets 612 are mounted on the plate 595 adjacent to the side arms 575 and slidably secure the racks 606 and the plates 610 to the face of the plate 595. One end of each of the U-shaped spreader arms 613 is pivotally connected to the plates 610, and the spools 614 are mounted on the other ends 45 of these arms respectively. The arms 613 are held to the plates 610 by the screws 615. The spring 616 is secured between the plate 610 and the arm 613 and presses the spool 614 against the face of the plate 595 under the groove 607.

The channel plate 617 rests on the inwardly projecting lugs 618 of the vertical arms 575 and is secured thereto. The channel plate 617 supports the anvil plate 619 having the forward edge adjacent to the parallel bar 107 beveled to coincide with the beveled bottom edge of the pressure plate 595. The pusher plate 620 is slidably mounted on the plate 619 and is guided by the downwardly bent edges which fit into grooves in the plate 619. The plate 620 extends rearwardly and is formed into a tube 621. The spring 622 is supported by the plunger tube 623 which is slidably mounted in the tube 621. The spring 622 presses the pusher plate 620 back into its

normal position. The cam 624 is mounted on the cam shaft 581 and works with the roll 625 mounted on the lever arm 626. The arm 626 is mounted on the shaft 627 supported in bearings in the side walls 573. The upper 70 end of the arm 626 abuts the end of the tube 621 of the pusher plate 620.

The cams 627 are mounted on each end of the cam shaft 581 and work with the rolls 628 respectively mounted on an end of the 75 arms 629. The arms 629 are mounted at their other ends respectively on the shaft 630 supported by the vertical arms 575. The brackets 631 are secured to the plate 590 and are provided with downwardly extending arms 632 secured to the arms 629 by the rod 633. The spacer rod 634 is mounted between the bracket arms 632. The lever arm 636 is mounted on the shaft 635 supported in suitable bearings in the side walls 573. The upwardly projecting arm 637 is secured to the lever arm 636 and is secured at its upper end to the link 640. The link 640 is mounted on the rod 641 supported by the bracket 632 which are secured to the end of each of the 90 racks 602.

The arcuate arm 638 is secured to the arm 637 and supports the roll 639. The roll 639 works with the cam 643 mounted on the stub shaft with the gear 583. One end of the 95 spring 644 is secured to the eye bolt 645 mounted on the plate 578, and the other end is secured to the arm 637. The spring 644 presses the roll 639 against the cam 643.

When the sheet unit is advanced into association with the pressing unit by the operation of the conveyor the crimp which was formed in the bound edge of the calendar rests on the plate 619. By the operation of the cam 624 with the roll 625 the arm 626 100 pushes the pusher plate 620 forward and the crimped edge of the calendar is positioned under the pressure plate 595 on the beveled edge of the plate 619. The arms 597 work with the knobs 598 and push the shafts 599 110 downward. The lugs 609 of the plates 610 slide downward on the lugs 608 and the spools 614 on the spreader arms 613 abut the top surface of the sheet units.

The cam 643 works with the roll 639 and 115 pushes the arm 637 rearward. The link 640 pulls the racks 602 rearward and the gears 603 rotate the shafts 599. The gears 604 work with the racks 606 and slide the spreader arms 613 outward. The spools 614 slide inward on the curved edges of the plate 595 and pull the string so that it will be projecting outward from the ends of the bound edge of the calendar. The cams 627 work with the rolls 628 and push the lever arms 629 120 downward. The bracket arms 632 cause the plate 590 to slide downward in the slots 577 and the pressure plate 595 flattens the crimped edge of the calendar, binding the edge of the calendar as shown in Fig. 40.

By the further operation of the cams 627 the springs 592 raise the plate 590 and the pressure plate 595 is raised, releasing the calendar. The cam 643 permits the spring 644 to pull the racks 602 forward and the spreader arms 613 are returned to their normal position. The cams 597 permit the springs 605 to push the shafts 599 upward, raising the spreader mechanism 596 from the surface of the calendar. The spring 622 pushes the pusher plate 620 rearward.

By the next operation of the driving mechanism, the conveyor is advanced another step and the roll 220 engages the concentric disc cam 651 mounted on the shaft 113 to push the gripper fingers 209 and 210 upward. The gripper is opened and the completed calendar is released from the conveyor. The finished calendar is delivered upon the plate 650 secured to the ends of the parallel bars 107 and 108, to be removed by hand or collected in any other suitable way.

I contemplate as being included in the invention or improvements herein set forth all such changes, variations, departures and modifications from what is thus specifically illustrated and described as fall within the scope of the appended claims.

I claim:

- 30 1. In combination, means for carrying a sheet unit in a fixed path of travel, and means operatively associated therewith for automatically securing a metal binding element and a hanger to an edge portion of the unit while in its path of travel.
- 35 2. In combination, means for carrying a sheet unit in a fixed path of travel, and means for securing a metal binding element and a hanger to an edge portion of the unit by a plurality of operations performed one after another in series while the unit is in its path of travel.
- 40 3. In combination, means for carrying a sheet unit in a fixed path of travel, and means including metal folding means, for applying a metal binding element to an edge portion of the unit while in its path of travel.
- 45 4. In combination, means for carrying a sheet unit in a fixed path of travel, and means, including means for forming a strip of metal, for applying a metal binding strip to an edge portion of the unit while in its path of travel.
- 50 5. In combination, means for carrying a sheet unit in a fixed path of travel, and means, including means for folding a metal strip and including means for folding together such folded strip and the edge portion of such unit, for applying a metal binding strip to an edge portion of such unit while in its path of travel.
- 55 6. In combination, means for carrying a sheet unit in a fixed path of travel, and means, including metal-folding means, for automatically

cally applying a metal binding strip to an edge portion of the unit while in its path of travel.

7. In combination, means for carrying a unit of assembled sheets in a fixed path of travel, and means, including means for forming a strip of metal substantially U-shaped for automatically crimping a metal binding strip upon an edge portion of the unit while in its path of travel.

8. In combination, means for carrying a sheet unit in a fixed path of travel, and means, including means for folding a strip and including means for folding together such in-folded strip and the edge portion of such unit, for automatically applying a binding strip to an edge portion of such unit while in its path of travel.

9. In combination, means for carrying a sheet unit intermittently step by step in a fixed path of travel with an interval of rest between the successive intermittent movements, and means, including binding element feeding means and a binding-element folding means, for securing a binding element to an edge portion of the unit while in its path of travel.

10. In combination, means for carrying a sheet unit intermittently step by step in a fixed path of travel with an interval of rest between the successive intermittent movements, and means, including means for feeding a strip of metal and forming it, for securing a metal binding strip to an edge portion of the unit by a series of operations sequentially performed while in its path of travel.

11. In combination, means for carrying a sheet unit intermittently step by step in a fixed path of travel with an interval of rest between the successive intermittent movements, and means, including means for feeding and folding a metal strip and including means for folding together such folded strip and an edge portion of such unit, for securing a metal binding strip to an edge portion of the unit by a series of operations sequentially performed while in its path of travel.

12. In combination, means for carrying a sheet unit intermittently step by step in a fixed path of travel with an interval of rest between the successive intermittent movements and means, including strip metal feeding and folding means for automatically securing a metal binding strip to an edge portion of the unit by a plurality of operations at different places in its path of travel.

13. In combination, means for carrying intermittently step by step in a fixed horizontal path of travel with an interval of rest between the successive intermittent movements a small number of loose sheets lying flat in the horizontal path and assembled as a unit, and means including means for forming a

- strip of metal for automatically crimping a metal binding strip upon an edge portion of the unit while in its path of travel.
14. In combination, means for carrying a flat and horizontally-lying sheet unit intermittently step by step in a fixed horizontal path of travel with an interval of rest between the successive intermittent movements, and means, including means for feeding and folding a metal strip and including means for folding together such folded strip and the edge portion of such unit, for automatically crimping a metal binding strip upon an edge portion of the unit while in its path of travel.
15. In combination, means including a substantially-horizontally-disposed endless-belt conveyor for carrying a sheet unit in a substantially-horizontal path of travel, and means associated therewith for automatically crimping a binding strip around an edge portion of the unit and for automatically securing a hanging bail thereto while in its path of travel.
16. In combination, means including a substantially-horizontally-disposed endless-belt conveyor having a flat and horizontally-disposed upper surface for carrying a sheet unit lying flat in a substantially horizontal path of travel with a period of rest between the successive intermittent movements, and means for interfolding a metal strip and an edge portion of the unit and pressing the folds tightly together by operations performed during rest periods intervening in its course of travel.
17. In combination, means including an endless-belt conveyor having a substantially flat upper surface substantially-horizontally-disposed and having automatically-operated grippers thereon for intermittently moving a sheet unit in a substantially horizontal path of travel with a period of rest between the successive intermittent movements, and means for automatically crimping a binding strip to an edge portion of the unit and for applying a hanger by operations performed during the rest periods intervening in its course of travel.
18. In combination, means including a substantially-horizontally-disposed endless-belt conveyor for carrying a substantially horizontally positioned sheet unit consisting of a small number of sheets in a substantially horizontal path of travel, and means for crimping a binding strip around an edge portion of the unit by a plurality of operations performed one after another in series while the unit is at different places in its path of travel.
19. In combination, means including an endless-belt conveyor having its upper surface substantially flat and substantially horizontally-disposed for carrying a sheet unit lying flat thereon in a substantially-horizontal path of travel, and means for automatically crimping a binding strip to an edge portion of the unit by a plurality of operations performed one after another in series while the unit is at different places in its path of travel.
20. In combination, means including a substantially-horizontally-disposed endless-belt conveyor for carrying a small number of sheets as a unit in a substantially horizontal path of travel, and means, including strip-feeding and strip-folding means, for crimping a binding strip to an edge portion of the unit while in its path of travel.
21. In combination, means including a substantially-horizontally-disposed endless-belt conveyor for simultaneously carrying a plurality of units of assembled sheets with a step-by-step movement in a substantially horizontal path of travel, each unit consisting of a small number of sheets, means on the conveyor for holding the units throughout the path of travel, means for feeding a metal binding strip into association with said sheet unit, and means for simultaneously operating upon each unit at each stage of the step-by-step movement, for crimping said metal binding strip to an edge portion of each unit while in its path of travel.
22. In combination, means including a substantially-horizontally-disposed endless-belt conveyor for carrying a unit of assembled loose sheets lying flat thereon in a substantially horizontal path of travel, means for automatically adjusting the sheets with respect to each other at the beginning of the path of travel, means for automatically clamping and holding the unit on the conveyor throughout the path of travel, and means, including means for feeding and folding a metal strip, and including means for folding together such folded strip and the edge portion of such unit, for automatically applying a metal binding strip to an edge portion of such unit while in its path of travel.
23. In combination, means including a substantially-horizontally-disposed endless-belt conveyor for carrying a thin unit of a few assembled loose sheets lying flat in a substantially horizontal path of travel, means for automatically adjusting the sheets with respect to each other at the beginning of the path of travel, means for holding the unit on the conveyor throughout the path of travel, and means, including means for folding a metal strip and including means for folding together such folded strip and the edge portion of such unit, for automatically applying a metal binding strip to an edge portion of such unit while in its path of travel.
24. In combination, means including a horizontally disposed endless-belt conveyor for carrying a unit of assembled loose sheets to a second endless-belt conveyor, a second

endless-belt conveyor, means associated with said conveyors for adjusting the sheets of the unit relative to each other, means for holding the unit on said second conveyor, and 5 means, including means for folding a metal strip, for automatically applying a metal binding strip to an edge portion of such unit while carried by said second conveyor.

25. In combination, means including a 10 horizontally disposed endless-belt conveyor for carrying a sheet unit in a fixed path of travel, means for positioning a flexible bail to be held by a metal strip at an edge portion of the unit, and means, including 15 means for folding a metal strip and including means for folding together such folded strip and the edge portion of such unit, for applying a metal binding strip to an edge portion of the unit and in holding engagement with such bail while the unit is in its 20 path of travel.

26. In combination, means including a 25 horizontally disposed endless-belt conveyor for carrying a unit of assembled sheets intermittently step by step in a fixed path of travel with an interval of rest between the successive intermittent movements, means for automatically positioning a flexible bail to be held at each end by a metal strip at 30 an edge portion of the unit, and means, including metal folding means, for automatically applying a metal binding strip to an edge portion of the unit in holding engagement with such bail while the unit is in its 35 path of travel.

27. In combination, means including a 40 horizontally-disposed endless-belt conveyor for carrying a unit of assembled loose sheets intermittently step by step in a fixed path of travel with an interval of rest between the successive intermittent movements, means 45 for automatically adjusting the sheets with respect to each other at the beginning of the path of travel, means for automatically clamping the sheet unit firmly upon the conveyor throughout its path of travel, means 50 for applying a flexible bail to be held by end portions of a strip folded upon an edge portion of the sheet unit, and means, including 55 means for automatically forming a strip of metal, for automatically applying a metal binding strip to an edge portion of the unit and in holding engagement to such bail while the sheet unit is in its path of travel.

55. 28. In combination, means for holding a sheet unit of the character described to receive a plurality of operations on an edge portion thereof, and means operatively associated therewith for automatically applying a binding element to an edge portion 60 of the unit through a succession of operations, and means for automatically applying a hanger for the unit, while the unit is so held.

65. 29. In combination, means for carrying a

sheet unit in a fixed path of travel, and means for binding the unit at one edge and applying thereto a suspending element by a plurality of operations at successive stages in the path of travel.

30. In combination, means for holding a 70 small number of sheets as a unit to receive a plurality of operations on an edge portion thereof, means for feeding to an edge portion thereof a metal strip, means for positioning a hanger to be held by the metal strip, and means for crimping the metal strip upon the edge portion of the unit and upon the hanger to hold the hanger thereto.

31. In combination, means for successively 80 delivering units of assembled sheets, means for jogging the units successively at the place of delivery, means for moving the jogged units intermittently step by step in a fixed path of travel with a period of rest between 85 the successive intermittent movements, and means for applying a metal binding element upon an edge portion of the unit by crimping the binding tightly upon and encompassing such edge portion by a succession of operations 90 one of which is performed at each of said successive rest periods.

32. In combination, means for moving a 95 unit of assembled sheets intermittently step by step in a fixed path of travel with a period of rest between the successive intermittent movements, means for applying a metal binding element along an edge portion of the assembled sheets and for forming a double fold therein and also a single fold of the 100 edge portion of the sheet unit encompassed by the binding, all as a succession of operations at least one of which is performed at each of said successive rest periods.

33. In combination, means for moving a 105 unit of assembled sheets intermittently forward step by step in a fixed path of travel with a period of rest between the intermittent movements, means for automatically applying to and around an edge portion of the 110 assembled sheets a metal strip formed with a portion substantially U-shaped in cross view, means for applying a hanging bail with its ends in position to be held by such strip, means for pressing said U-shaped portion 115 upon the edge portion of the assembled sheets and upon the ends of such bail, and means for folding over a portion of said strip and the edge portion of the assembled sheets at said strip and pressing the folded-over parts 120 upon each other, all as a series of operations each of which is automatically performed at a different one of the rest periods.

34. The combination of an endless belt conveyor having its upper surface travelling in substantially a horizontal plane, with means for moving the conveyor intermittently step by step, means for delivering sheet units successively to said conveyor at one end thereof, 125 means for automatically jogging the deliv- 130

ered units successively to adjust them with respect to each other, means for holding the units upon the conveyor after being jogged, a plurality of mechanisms arranged along a common edge of the conveyor, the units respectively being carried by the conveyor to have an edge of each thereof come into association with said mechanisms, one after the other, said mechanisms including means for arranging a flexible bail at the edge portion of each unit where operated upon, others of

said mechanisms comprising means for feeding a strip of thin metal into association with the edge of each unit operated upon and folding said metal, together with edge portions 15 of the unit, to crimp the strip as a narrow binding upon and around the edge portion of the unit, respective operations of said mechanisms being performed at respective rest periods between intermittent movements 20 of the conveyor.

LE ROY BURDETT.
